UNITED STATES PATENT OFFICE.

JOHN MOOTERY BROWN, OF HAMILTON, ONTARIO, CANADA, ASSIGNOR TO THE BROWN, BOGGS CO. LIMITED, OF HAMILTON, ONTARIO, CANADA, A JOINT-STOCK COMPANY OF ONTARIO.

CRIMPED-ELBOW-BENDING MACHINE.

1,340,320.

Specification of Letters Patent.

Patented May 18, 1920.

Application filed July 24, 1919. Serial No. 312,917.

To all whom it may concern:

Be it known that I, JOHN MOOTERY BROWN, of the city of Hamilton, in the county of Wentworth, Province of Ontario, Dominion 5 of Canada, have invented certain new and useful Improvements in Crimped-Elbow-Bending Machines, of which the following is a specification.

My invention relates to improvements in 10 crimped elbow bending machines, and the object of the invention is to devise a machine of this class which will expeditiously bend a perfect elbow of this class.

Figure 1 is a side elevation partly in section showing my improved crimped elbow bending machine in its initial position preparatory to bending the elbow.

Fig. 2 is a similar view with portion of the frame broken away.

Fig. 3 is an end elevation looking toward the cap end.

In the drawings like characters of reference indicate corresponding parts in the various figures.

1 is the base frame of the machine at one end of which is a standard 1'. 2 is a standard plate, which is secured on the base 1 as indicated by the cross plate 2' which forms part of the standard plate. 3 is a cylinder 30 former, which has end flanges 3' by which it is secured by suitable bolts 3' to the standard plate 2. The plate 2 has a central orifice 2'.

4 is the interior forming die or mandrel which has an arc-shaped outer end 4' around 35 which the elbow is designed to be bent and a reduced inner end 4', which fits the orifice 2' and is provided with a reduced threaded outer end 4' upon which is fitted the nut 5, which thereby secures the interior forming 40 mandrel in position. The interior mandrel 4 is provided with slots 4' located diametrically opposite to each other.

7 is a cross bar, which extends through the end of the slot 4' and carries a rod 8, which 45 derives movement as will hereinafter appear.

9 is a collar, which extends around the interior forming mandrel 4 fitting the space between it and the outer cylinder 3. The collar 9 abuts the cross bar 7 and is provided with a groove 9' to receive the end of 50 the pipe.

10 is a retaining cap, which is held on the end of the cylinder 3 by means of bell cranks 11, one on each side of the cylinder, the

hooked ends 11' of which extend over a 55 pin 10'.

The opposite ends of the bell cranks are held by means of the spiral springs 11' and thereby hold the hook in position on the pin 10'. 60

The interior of the cap 10 is provided with a groove 10' to receive the opposite end of the pipe, which is designed to form the elbow. This pipe it will be noticed is a crimped pipe and it is necessary to have it 65 crimped in order to form the elbow.

I do not describe the manner in which the pipe is crimped as it forms no part of my invention.

The cap 10 has a lug 10' formed on the 70 outside provided with a pin 12 for a purpose which will hereinafter appear. 13 is a guide-way which is supported on the top of the cylinder 3. 14 is a slide bar, which extends through the guide-way and has pivotally connected to the outer end the arm 15, which is provided with a hooked end 15'. The slide bar 14 is provided with a stop 14', a notch 14', an inclined side next the stop and a stop 14' and an inclined end 14'. 80

16 is an upright through which the slide 14 extends. The lower end of the upright 16 is provided with a headed screw 17 which is adjustable therein.

The rod 8 hereinbefore referred to is connected to the ram 8' as is also the upright 16. The ram 8' derives movement from the crank shaft in the ordinary manner as in power presses. 85

As the means for driving the rod 8 and 90 its parts form no feature of my invention I do not further describe it except to say that the ram is thrown into and out of gear as is usual by the foot lever 18 in the manner ordinarily incident to presses of this 95 class.

In order to relieve the jar and noise I provide a cushion washer 14' to the inside of the stop 14'.

It is necessary that means should be provided to release the cap 10, and I therefore utilize a rod 19, which passes through the upright 3', and a guide 20 and has a spring 21 extending between the upright 3' and the nut 22 on the rod. The rod is opposite the 100 set screw 17. This rod is as will be seen opposite the bottom end of the bell crank 11.

Having now described the principal parts

involved in my invention I shall briefly describe its operation and utility.

Preliminarily the cap 10 is removed and the corrugated pipe as indicated in Fig. 1 is inserted with the inner straight edge in the groove 9' of the collar 9 surrounding the inner mandrel 4. The cap 10 with its groove 10² is placed in position, so that the outer end of the crimp pipe fits into the groove 10², the cap being held in place by the spring held bell cranks 11 one on each side. The machine is then ready to operate. The ram 8' is caused to move forward carrying with it the upright 16 and also the collar 9 by means of the cross bar 7, thereby serving to compress the crimping pipe into more contracted form. The upright 16 in the movement of the rod 8 carries with it the stop 14' and consequently the slide bar 14 and hooked end of the arm 15 past the pin 12. At the same time the headed screw 17 pushing on the rod 19 releases the bell crank 11 and at this point the retrograde movement takes place and hook of the rod 15 engages the pin 12, and the slide bar 14 as it draws on the arm 15 swings up the cap 10 and thereby expanding the previously crimped pipe into the form of a crimped elbow, the wider portions of the crimp being necessarily on the long side of the elbow as indicated.

This retrograde movement is caused by the bar 16 engaging the square end of the notch 14² as indicated in Fig. 2 and such engagement continues until the inclined end of the bar 14 reaches the inclined top of the bar 16², which raises the slide bar 14 so as to release the slot in the bar 16 from engagement therewith and thus allows the bar 14 to come up to the stop 14³, which is its normal position.

When the elbow is crimped the hooked end of the bar 15 is unhooked and the cap 10 removed and the crimped elbow taken out completed. The new corrugated piece of pipe is then placed in position as before and the cap 10 replaced and held in position by the hooked end of the bell crank 11 ready for another operation.

From this description it will be seen that by a machine made according to my invention I am enabled to bend and compress a pipe into the form of an elbow in one continuous operation which is an important desideratum.

What I claim as my invention is:

1. In a crimped elbow bending machine, the combination with the outer cylinder suitably supported on the frame, of an inner cylinder forming an interior annular chamber to receive a crimped blank with the outer cylinder, means for contracting the crimps within the chamber, and means for ejecting the contracted pipe and bending the same as it is being ejected.

2. In a crimped elbow bending machine, the combination with the outer cylinder suitably supported on the frame, of an inner cylinder forming an interior annular chamber with the outer cylinder, a cap for the outer end of the cylinder, means for normally holding the cap in position while the pipe is being crimped and means for swinging the cap outwardly and upwardly as the pipe is being ejected. 75

3. In a crimped elbow bending machine, the combination with the outer cylinder and standard plate supporting the same having a central orifice and the inner cylinder provided with a closed threaded end extending through the orifice and provided with slots diametrically located, of the ram and rod thereof extending through the reduced end of the inner cylinder and provided with a cross bar extending through the slots, a collar surrounding the inner cylinder and abutting the cross bar and provided with receiving groove for one end of the pipe, a cap provided with a receiving groove for the opposite end of the pipe and means for releasing the cap and swinging it upwardly. 80 85 90

4. In a crimped elbow bending machine, the combination with the outer cylinder and standard plate supporting the same and having a central orifice and the inner cylinder provided with a closed threaded end extending through the orifice and provided with slots diametrically located, of the ram and rod thereof extending through the reduced end of the inner cylinder and provided with a cross bar extending through the slots, a collar surrounding the inner cylinder and abutting the cross bar and provided with a receiving groove for the opposite end of the pipe, pins on the cap, a bell crank having a hooked end extending over the pins and spring held, and means for releasing the hooks of the bell-crank. 95 100 105

5. In an elbow bending machine, the combination with the outer cylinder and standard plate supporting the same and having a central orifice and the inner cylinder provided with a closed threaded end extending through the orifice and provided with slots diametrically located, of the ram and rod thereof extending through the reduced end of the inner cylinder and provided with a cross bar extending through the slots, a collar surrounding the inner cylinder and abutting the cross bar and provided with a receiving groove for one end of the pipe, a cap provided with a receiving groove for the opposite end of the pipe, means for holding the cap in position, an upright secured to the rod of the ram and provided with an adjustable bolt and a spring-held rod designed to be operated by the bolt to release the cap. 110 115 120 125

6. In a crimped elbow bending machine, the combination with the outer cylinder and standard plate supporting the same having 130

a central orifice and the inner cylinder provided with a closed threaded end extending through the orifice and provided with slots diametrically located, of the ram and rod 5 thereof extending through the reduced end of the inner cylinder and provided with a cross bar extending through the slots, a collar surrounding the inner cylinder and abutting the cross bar and provided with receiving groove for one end of the pipe, a cap provided with a receiving groove for the opposite end of the pipe, means for releasing the cap, an upright secured to the rod of the ram, an upright secured to the frame 10

provided with an inclined upper end, a slide 15 rod extending through the upright and provided with an inclined end to engage the inclined end of the upright on the frame, stops on the slide rod, an arm at the opposite end of the rod provided with a hooked end, a 20 guideway for the slide rod and a bracket on the cap provided with a pin with which the hooked arm is designed to engage.
